233,113

TOWEL OR SIMILAR ARTICLE

Nancy Ann Scherer, Plainfield, N.J., assignor to Cannon
Mills Company, Kannapolis, N.C.

Filed Nov. 2, 1972, Ser. No. 303,135

Term of patent 14 years

Int. Cl. D6—13

U.S. Cl. D6—265

FIG-1

FIG. 1 is a top plan view of a towel or similar article showing my new design; and

FIG. 2, is a top plan view of a second embodiment of the design shown in FIG. 1.

I claim:

The ornamental design for a towel or similar article, substantially as shown and described.
